[57] CLAIM

The ornamental design for a detachable multi-purpose light platform, as shown and described.

DESCRIPTION

FIG. 1 is a top plan view of a detachable multi-purpose light platform showing my new design;

FIG. 2 is an elevational view of one side, the opposite side being substantially a mirror image thereof;

FIG. 3 is a front elevational view;

FIG. 4 is a rear elevational view; and,

FIG. 5 is a bottom plan view.

The twin lamps and support surface are shown in broken lines for illustrative purposes only.
